CIRCULAR KNITTING MACHINE

Frank R. Page, Laconia, N. H., assignor to Scott & Williams, Incorporated, Laconia, N. H., a corporation of Massachusetts

Application October 3, 1946, Serial No. 700,993

7 Claims. (Cl. 66—57)

1
This invention relates to stitch cams for circular knitting machines using latch needles. It is an object of this invention to provide a needle-operating or stitch cam of improved construction which will draw down the needles in such manner that engagement of the needle latches with the hooks will be uniform, and the knitting of tuck stitches because of improper positioning of the needle latches with respect to the hooks will be prevented. Another object is to provide a stitch cam which will prevent cutting of the yarn by the latch of the needles.

In the drawings:

Fig. 1 is a view in elevation of a stitch cam for a circular knitting machine in accordance with this invention, the cam being shown as it would appear viewed from outside the needle circle;

Fig. 2 is a diagrammatic view showing the relation of the cam and needles in the operation of the needles as they would appear from the outside of the needle circle, only each third needle being shown; and

Fig. 3 is detail views of the needle hooks showing their relation to the latch pivot line and the yarns at the point where the latches are closing.

The invention is shown in connection with a needle-operating or stitch cam 1 such as is used in circular knitting machines having independent latch needles and rotating needle cylinders, although the invention is equally applicable to knitting machines having rotating cam rings and fixed needle cylinders. As shown, the cam comprises a triangular piece of metal having a suitable curved face adjacent the needle cylinder, a central opening 2 to receive the bolt by which it is secured to the cam ring, an inclined face 3 which serves to draw down the needles by engaging the butts thereof and a straight inclined face 4 which meets the face 3 at the lowest point or apex 5 and which cooperates with another cam (not shown) in guiding the raising of the needles. The face 3 of the cam 1 is hollow-ground for a portion of the face spaced from the apex 5 so that face 3 comprises an upper straight portion 3a, a curved portion 3b and a lower straight portion 3c. The lower straight portion 3c, however, is offset or set back to the right from what its position would be if the curved portion 3b were not interposed between the straight portions 3a and 3c. The casting off level of the machine is indicated by the dotted line 9 in Figs. 2 and 3, and the path of the pivot points of the latches of the needles is indicated in Fig. 3 by the dot-and-dash line 10.

2
In the knitting of hosiery the needles N are raised by other cams (not shown) to take the yarn, and the needles are then drawn down by the engagement of the needle butts 8 by the face 3 of the cam 1 to draw a loop of the yarn through the previously drawn loop and to cast off the previously drawn loop. As each needle is drawn down, the previously drawn loop held by the needle is raised on the needle shank so that it closes the latch, passes over the needle hook and is cast off. In the knitting of hosiery of very fine gauge at high speed there is a tendency for the latch, when closed by the loop being cast off, to take a position at one side or the other of the needle hook, so that the latch, instead of covering the hook point and being positioned to guide the loop over the hook, is positioned so that the loop being cast off is caught by the needle hook and retained by the needle. The needle therefore knits a tuck stitch.

To overcome this objection, the cam is hollow-ground on the draw-down side, leaving a straight portion 3a of sufficient length that the needle is drawn down at the usual speed until the loop being cast off begins to raise the needle latch above a horizontal position, as shown in Fig. 3.

At this point, the needle butt engages a curved portion 3b of the cam face 3 which provides a lesser rate of descent for the needle. This slows the closing of the latch by the loop being cast off and insures the latch being properly seated on the needle hook. As a result the needle cannot retain the loop. The curved portion 3b extends a sufficient distance to insure the proper closing of the latch but the remainder 3c of the cam face is finished as a straight surface. The inclination of the straight surface 3c to the horizontal may be slightly greater than that of the upper straight surface 3a, the straight part 3c being shown at a 50° angle while 3a is at 45°. The curved portion 3b merges into the straight portion 3c and the speed of lowering of the needle therefore is gradually accelerated to the speed given by the portion 3c.

Forming the curved portion 3b in the cam face taken with the straight portion 3c offsets the lower end or apex 5 of the cam in the direction of rotation of the needles in rotary knitting, causing each needle to be further along in its travel about the machine before the loop is cast off from the needle. This changes the angle of the yarn as it passes from the yarn-finger to the stitch just knit. As a result the yarn engages the needles at a higher point thereby lessening the danger of the yarn being pinched.

by the latch against the rivet cheeks and the yarn cut as the latch is closed. This is particularly important where plating yarns are being fed to the needles.

It will be seen that the new cam face not only has a hollow part to give the advantage of a slower closing of the needle latch but has a straight lower part to cast off the stitch which therefore has all the advantages of a plain cam face, i. e. is not hollow ground. This lower portion gives the needles a uniform rate of movement. The parts of the cam face are so united that the cam engages the yarns at a higher point on the needle when the latch is closing, thereby avoiding cutting of the yarns and yet the speed of closing of the latches and the speed of cast off are independent of each other.

What I claim is:

1. In a circular knitting machine having independent latch needles, a stitch cam having a needle draw-down surface comprising spaced upper and lower straight portions and an intermediate curved portion merging into said lower straight portion, said curved portion operating said needles during the time the latches are closing beginning about the time the latches start to close, said lower straight portion lowering said needles at a greater speed than said upper straight portion, and said curved portion lowering the needles only at a speed less than that of said upper straight portion.

2. In a circular knitting machine having independent latch needles, a stitch cam having a needle draw-down surface consisting of an upper straight portion for drawing the needles down at a predetermined rate, a curved portion for drawing each needle down at a slower rate until the needle latch is closed and a lower straight portion for drawing the needles down at a uniform rate greater than said predetermined rate for casting off the previously drawn loops.

3. In a circular knitting machine having independent latch needles, a stitch cam having a needle draw-down surface comprising spaced straight portions connected by an intermediate curved portion, the curved portion being so shaped and located as to provide a lowering of the needles beginning substantially with the closing of the latches which is slower than the lowering of the needles on the straight portions.

4. In a circular knitting machine having independent latch needles, the combination of yarn feeding means, independent latch needles whose latches cast off the stitches, and a stitch cam having a needle draw-down surface comprising spaced straight portions connected by an intermediate curved portion so shaped and located with relation to the needle latches as to provide a lowering of the needles during the closing of the latches that is slower than the lowering on the straight portions.

5. In a circular knitting machine having independent latch needles, the combination of yarn feeding means, independent latch needles whose latches cast off the stitches, and a stitch cam having a needle draw-down surface comprising spaced upper and lower straight portions and an intermediate curved portion merging into said lower straight portion, said curved portion being so curved and located with respect to the needle latches as to operate said needles beginning substantially with and during the time the latches are closing, said lower straight portion being adapted to lower said needles at a greater speed than said upper straight portion, and said curved portion being adapted to lower the needles at a speed less than that of said upper straight portion.

6. In a circular knitting machine having independent latch needles, the combination of yarn feeding means, independent latch needles whose latches cast off the stitches, and a stitch cam having a needle draw-down surface consisting of an upper straight portion for drawing the needles down at a predetermined rate, a curved portion beginning at a point corresponding with the time when the needle latches begin to close and so curved and located with respect to the needle latches as to draw each needle down at a slower rate while the needle latch is closing, and a lower straight portion adapted to draw the needles down at a uniform rate greater than said predetermined rate for casting off the previously drawn loops.

7. In a circular knitting machine having independent latch needles, a stitch cam having a needle draw-down surface comprising spaced upper and lower straight portions and an intermediate curved portion, the curved portion being so curved and located with respect to the needles that it begins to lower them at a lesser rate about the time the latches begin to close, the lower straight portions being so located as to lower the needles at a greater rate than said upper straight portion.
